UNITED STATES PATENT OFFICE.

JOHN W. DEARSLEY, OF RACINE, WISCONSIN.

MOLDING MACHINE.

Application filed December 12, 1921. Serial No. 521,751.

To all whom it may concern:

Be it known that I, JOHN W. DEARSLEY, a citizen of the United States, and resident of Racine, in the county of Racine and 5 State of Wisconsin, have invented certain new and useful Improvements in Molding Machines; and I do hereby declare that the following is a full, clear, and exact description thereof.

10 The invention relates to a molding machine and methods for molding sheaves and similar objects, either as entire annuli or segments.

Hitherto the manufacture of objects, such 15 as sheaves and rims, has been attained with considerable difficulty.

The invention has, as its object, the facilitating of the manufacture of sheaves, rims, etc., which may be of a crescent or 20 like shape in cross section. Up to the present difficulty has been experienced in making patterns for objects of this nature, and in removing the patterns from the sand. Again, the processes employed are laborious 25 and slow.

The invention contemplates the provision of a three part flask. A plate with a portion of a pattern rigid or integral therewith is provided to cooperate with the cope 30 or drag which are placed thereon successively to produce in the sand packed in said cope or drag, a desired indentation conforming to the outline of the sheave it is desired to make. The molds made in the cope and 35 drag are identical.

Means are provided for forming sand upon a cheek in such manner as to produce a shape that fits in with the outer surface 40 of the sheave that is being made so that the cope, cheek and drag may be assembled and produce a complete mold of the sheave. In forming the sand on the cheek, the cheek is positioned upon a pattern member, the lower surfaces of the cheek being especially 45 shaped to rest snugly upon the upper surfaces of the pattern member, and a ring is placed on the pattern member and secured rigidly in position. The sand is then packed in among the cheek, the pattern member and the ring, and a pivoted strike is swung along the upper surface of the cheek and the sand shaped properly, the excess being removed. This sand is subjected to the customary hardening processes and the cheek 50 is then ready for reception in the flask.

Objects of the invention are rapidity and ease of operation, simplicity of the parts of the machine, readiness of manufacture of the machine and superiority of operation of the device, the castings being uniformly 60 excellent.

Other objects and advantages will appear as the description proceeds.

Reference is had to the accompanying drawings, in which

Figure 1 is a plan of the cope, a part being broken away.

Figure 2 is a cross section on the line 2-2 of Figure 1 of the flask.

Figure 3 is a cross section through the 70 cope and pattern plate.

Figure 4 is a plan of the cheek and such parts of the machine as cooperate therewith for forming the outer face of the mold.

Figure 5 is a central vertical section thru the cheek and pattern plate in assembled position.

The same reference characters refer to the same parts throughout the figures.

The shape of the complete mold 10 is shown in Figure 2. The invention contemplates considerable variation of this shape. In order to produce the upper part 11 of this mold, pattern plate 12 is provided, having a pattern 13 integral therewith. Nipples 14 are provided on the pattern plate for the reception of pipe legs 15. A circumferential flange 16 is downwardly directed from the circumference of the pattern plate. This serves to give strength but does not add excessively to the weight.

In Figure 3, the cope is shown positioned on the pattern plate. Cope 17 and drag 18 are substantially similar in shape. Vertical walls 19 and 20 rigid with each other are provided in the cope 17, from the outer surface of wall 20, a horizontal surface 21 on brace 22 is directed for a distance, then a surface arcuate in shape is upwardly directed to wall 19.

When the cope is assembled with respect to pattern plate 12, as shown in Figure 3, sand is packed in between braces 22 of the cope and acquires the shape shown in Figure 2. Handles 23 rigid with the cope are provided to facilitate handling, and lugs 24 are provided on both cope and drag for the reception of pin 25, to facilitate proper assembling of the parts of the flask.

It is apparent that the shape of the pattern plate is such as to provide for the upper, lower and inner faces of the mold. In Figure 5 is shown the machine for making the outer face thereof. A pattern member 26 is provided, having suitable supports 27 and arms 28. Ring 29 may be assembled with or removed from pattern member 26, and handles 30 rigid with shafts 31 operate 10 to move clamps 32, the inclined faces of which engage with head 33 of pins 34 for tightening ring 29 against pattern member 26. The surface formed on the sand resting on cheek 35 is apparent both in Figure 15 and in Figure 2 in which the cheek is shown assembled in the flask. Cheek 35 is provided with an inwardly directed flange 36. The lower surfaces 37 and 38 rest snugly upon pattern member 26. Flange 36 serves 20 to support the sand after cheek 35 is removed from pattern member 26 and ring 29. A hub 39 is rigid with arms 28 and chambered to receive a pin 40 having a collar 41 and a reduced portion 42 threaded to receive 25 a nut 43 which holds bracket 44 in position against hub 39 but permits rotation thereof about a pin 40. A strike 45 is pivoted at 46 on bracket 44, and is provided with a knife 47 having a projection 48 for forming the upper face of the sand resting on cheek 35. The lower surfaces of knife 47 rest snugly upon ring 29 and cheek 35. Cheek 35 is provided with a lug 49 having a pin 52 therein inserted through 35 an aperture in lug 50 on pattern member 26 to facilitate proper centering and prevent the rotation of cheek 35 when strike 45 is rotated. After the sand has been suitably packed on the cheek and its upper face 40 has been formed by knife 47, it may be subjected to common molding processes, such as baking, if desired, to facilitate its ready assembly with the drag and cope. The formation of the mold in the drag and cope 45 has been described.

The drag, cheek and cope are assembled, as shown in Figure 2, lugs 51 on the drag cooperating with pin 52 to center the cheek properly with respect to the drag. Suitable vents are provided for the pouring in of the metal into the mold. These may be made when the cope and drag are on the pattern plate.

It is apparent that on the assembly of 55 the parts of the flask, the desired shape of mold 10 results.

I have, therefore, provided an exceedingly simple device, rapid in its operation for making a desired shape of mold. No difficulty is experienced in withdrawing pattern 13 from the sand, and the parts are readily assembled and a casting of the proper shape necessarily results.

The simplicity of the operations performed on the cheek is especially apparent, 65 the mere rotation of strike 45 giving the desired upper surface to the sand and the turning of handles 30 frees ring 29 and permits its removal and the freeing of cheek 35.

While a preferred embodiment of the invention has been illustrated and described, 70 it is to be understood that the present invention is not confined to such specific embodiment, but may be otherwise embodied within the spirit of the invention and the 75 scope of the following claims; and it will further be understood that a substantial range of equivalence is contemplated.

I claim:

1. In a molding device, the combination 80 of a drag and a cope having inner and outer members, and a cheek adapted to be positioned between said cope and drag, said cheek having a flange projecting towards the inner members of said cope and drag. 85

2. In a sheave molding device, the combination 90 of a cope, a drag, and a cheek having an inwardly directed flange, said cope and drag having an inner and an outer portion held together by intermediate braces and adapted to receive sand between said inner and outer portions and across said intermediate braces and permit molding of 95 said sand, said cheek being adapted to support a molded sand ring in cooperative relation to the molded sand in said cope and drag.

3. In a molding device, the combination 100 of a drag, a cheek, and a cope adapted to be arranged in the order recited with one resting upon the other, said cope and drag having inner walls adapted to contact, and having outer walls adapted to engage said cheek, said cheek having an inwardly projecting flange located within the space between the inner and outer walls of said cope and drag. 105

4. A molding device having a pattern member, a bracket revolvably mounted relatively to said pattern member, and a striker pivoted to said bracket, whereby said striker may be rotated with said bracket or may be pivotally moved relatively to said bracket. 110

5. A molding device having a pattern member, a ring thereon, a bracket revolvably mounted relatively to said pattern member, and a striker pivoted to said bracket, whereby said striker may be rotated with said bracket or may be pivotally moved relatively to said bracket. 115

In testimony that I claim the foregoing I have hereunto set my hand at Milwaukee, in the county of Milwaukee and State of Wisconsin.

JOHN W. DEARSLEY.
